UNITED STATES PATENT OFFICE.

TRULS LOKEN, OF KENOSHA, WISCONSIN, ASSIGNOR TO AUSTIN MACHINERY CORPORATION, OF CHICAGO, ILLINOIS, A CORPORATION OF ILLINOIS.

TRENCHING MACHINE.

Application filed February 11, 1924. Serial No. 691,857.

The invention relates to trenching machines and has particular reference to that class of trenching machines having at the rear end thereof a swinging boom, or bucket support, and in which the excavating is performed by endless series of buckets which are caused to travel up and down the said boom by means of sprocket chains, or other endless members, whereby the buckets are filled while moving upward against the end wall of the trench and in which each bucket discharges its load when turned upside down at the upper end of its upward path of travel; each bucket, for this purpose, being provided with an open inner side to permit the dirt to enter the open mouth of the bucket and pass entirely through the latter. This operation of filling and discharging the bucket takes place continuously through the rotation of the sprocket chains, and the upper end of the boom, or bucket-carrying support, is provided with an adjusting device for tilting the boom about a horizontal axis and in a vertical plane, thereby varying the working depth of said buckets, depending upon the depth of trench desired.

Generally stated, the object of the invention resides in the provision of a novel and highly efficient trenching machine of the foregoing general character.

One of the objects of the invention is to provide a trenching machine, of the character described, having means for continuously and effectually discharging the contents of each bucket as it reaches the uppermost point in its path of travel, said bucket discharging means being designed to function without possibility of breakage due to the passage of stone, or other foreign matter, through the buckets, and to further operate effectively regardless of the consistency, or moisture content, of the material being excavated.

A still further object of the invention resides in the provision of certain details and features of construction and novel combinations tending to increase the general efficiency and serviceability of an excavating machine of this particular character.

With such objects in view, as well as other objects which are incident to the use of the improvement, the invention consists in the parts and combinations thereof hereinafter set forth and claimed.

In order to make the invention more clearly understood, there are shown in the accompanying drawings means for carrying the same into practical effect, without limiting the improvements, in their useful application, to the particular construction which, for the purpose of explanation, has been made the subject of illustration.

In said drawings:

Figure 1 is a detail vertical sectional view of the upper portion of the boom, or bucket support, which is mounted at the rear end of the machine, and illustrating the sprocket chains on which the buckets are mounted, as well as the construction and operation of the ejector, or bucket cleaner devices, and also illustrating the manner in which the buckets discharge while passing around the sprocket wheels at the upper end of the boom;

Fig. 2 is a detail rear elevation of the upper portion of the boom and illustrating more particularly the bucket cleaner mechanism shown in Fig. 1;

Fig. 3 is an enlarged detail section, taken on the line 3—3 of Fig. 1;

Fig. 4 is an enlarged transverse section taken on the line 4—4 of Fig. 2; and

Fig. 5 is an enlarged perspective view of the plate which constitutes the ejector and cleaner, and which is of a shape and character to scrape the entire surface of each bucket, whereby the said ejector, or cleaner, through relative movement, passes entirely through each bucket.

Referring to the drawings, 1 indicates the rear portion of a trenching machine frame having attached thereto, by means not shown, an auxiliary frame portion, or super-structure 2, having at its rear end a bearing portion in which is suitably journaled a transverse shaft 3. The boom, or bucket support, 4 is mounted to swing upon the shaft 3 and comprises a lower portion consisting of opposed channel members 5, secured together and in spaced relation, as by the upper and lower plates 31 bolted or riveted thereto, and adapted to project or depend downwardly into the trench, and opposed upper portions, or members, 6 secured thereto and rotatably secured to the shaft 3 by means of the bearing blocks 7. The members 6 are secured together in spaced relation, as by bolts bolted or riveted thereto as at 33. The shaft 3 is provided with a pair of sprocket wheels 8, preferably hexagonal, or otherwise poly-

90

115

onal, in shape and suitably spaced from one another, over which are adapted to pass the endless sprocket chains 9. A lower shaft (not shown), similar to the shaft 3 and having sprocket wheels similar to the wheels 8, is mounted at the lower end of the boom, or bucket support 4 within the ditch over which pass the lower portions of the endless sprocket chains 9. Suitable idler pulleys 10 are provided at intervals along the boom over which the sprocket chains pass on their downward passage toward the trench. The upper shaft 3 is further provided with a preferably larger sprocket wheel 14 over which passes a second sprocket chain 15 by means of which the sprocket wheels 8 and chains 9 are rotated from the machine by any suitable source of power (not shown here).

A suitable or desired number of buckets 11 are secured at intervals to the links of the chains 9, each bucket being preferably rigid with two parallel links of said chains and each bucket being preferably of rounded, or turtle-back formation to provide an opening at each end, the said rounded formation of the bucket providing a receptacle for the material to be excavated when the buckets are in their normal position, traveling up or down with the sprocket chains. Each bucket has its cutting edge, or lip, provided with flared digging teeth 12 and its sides provided with corresponding flared teeth 13, whereby the trench being excavated is wider than the combined width of the sprocket chains to permit freedom and flexibility of operation.

Referring to Fig. 1, it will be observed that on their upward journey, the hexagonal shape of the sprocket wheels 8 causes the buckets 11 to tilt outwardly away from the sprocket chains in position to have their contents discharged therefrom and that while traveling toward or from said sprocket wheels 8, the buckets rest tightly against the sprocket chains in position to carry or receive a load of material from the trench. At their upper extremity of travel, the buckets pass between the upper frame members 6 of the bucket supporting boom 4.

A frame member, or yoke, 16 is secured as by a suitable pivot 17 to the upper portion of the boom, the upper parallel deflected arms of the yoke being offset and between which is pivoted, as at 18, the bucket cleaner 19. The cleaner 19 has secured thereto, at its upper portion, a plate 20 of sufficient width to traverse the interior of the buckets with a slight clearance, in order to effectually eject the contents of the buckets as they successively reach the cleaner. The cleaner 19 further comprises a depending arm 21, having a pivot portion 22 to which is secured the upper end of a rope, or cable 23. The latter extends from the arm 21 of the cleaner, over an idler 24, suitably secured to the upper portion of the opposed channel members

5 of the boom, and thence extends downwardly between the channel members and is secured at its lower end, as at 27, to one end of a weight, or block 25. As best seen in Figs. 2 and 4, the latter is provided with 70 wheels, or runners, 26 to provide for substantially frictionless reciprocation of the weight, or block 25 along and between the opposed channel members 5 of the boom when the cleaner is in operation. 75

The operation of the improved cleaning device above described will be apparent. When a bucket containing a load of material reaches the point where it is tilted away from the sprocket wheels 8, as shown in 80 Fig. 1, the plate 20 of the cleaning device enters the bucket and impacts against the material contained therein. The pressure of the material contained within the moving bucket tends to rock the cleaner 19 on its pivot 18, thereby moving the weight, or block 25 upwardly on its runway between the channel beams. Should the material contained in the buckets be of a loose or dry character, the weight alone of the block 25 is 85 sufficient to expel the material from the bucket without rocking the cleaner on its pivot 18. However, should the material be of a heavy or moist character, its tendency would be to resist the pressure of the cleaning plate 26, thereby rocking the cleaner on its pivot and raising the weight an appreciable distance. Consequently, when the tendency of the sticky material to adhere has been overcome by continued travel of the bucket, the weight 25, together with its rolling contact with the beams, causes it to return suddenly to its normal position, thereby rocking the cleaner 19 on its pivot with sufficient force to suddenly and completely 90 eject the contents of the bucket from the bucket and into the hopper 28, and thence to the endless belt, or conveyer 29, whereby the ejected material is immediately discharged at 95 a point remote from the trench. 100

It will be further apparent that, should an obstruction, such as a wedged stick or stone, or the like, come in contact with the cleaner 19, its manner of mounting described serves to effectually prevent any danger of breakage of any part, as the foreign matter lodged in the bucket will overcome the weight of the block 25 sufficiently to pass over the cleaner, without damaging the same, after which the block 25 will return the cleaner to its normal cleaning position. It will be further apparent that the size or weight of the block 25 may be varied to meet existing conditions and to insure an efficient functioning of the cleaning mechanism in different varieties of soil. The cleaning plate 25 travels in an arc of obviously lesser radius than the arc of the bucket body, which further serves as an insurance against the cleaner wedging against the bucket body while passing there- 110 115 120 125 130 135

through. A shield, or guard, 30 is provided to enclose the buckets while traveling upward from the trench to effectually prevent the material excavated from being spilled 5 upon the ground and to direct it back into the trench.

It is thought that the invention and many of its attendant advantages will be apparent as it is better understood from the foregoing 10 description, and it will be apparent that various changes may be made in the form, construction and arrangement of the parts without departing from the spirit and scope of the invention, or sacrificing all of its material advantages, the form hereinbefore 15 described being merely a preferred embodiment thereof.

I claim:

1. In a trenching machine, in combination: 20 a frame, a boom mounted to swing with respect to said frame, an endless series of digging and conveying buckets mounted for longitudinal travel with respect to said boom, said buckets being adapted when at a determined point of said travel to tilt into dumping position, a cleaner pivotally mounted on said boom and adapted to pass successively through said buckets while the latter are in dumping position, a gravity controlled weight mounted within and for reciprocation along said boom and adapted to control said cleaner while passing through 30 said buckets, and anti-friction means carried by said weight.

35 2. In a trenching machine the combination of, an endless conveyor, a plurality of buckets carried by said endless conveyor, and

a bucket cleaner, said cleaner being arranged to pass through the buckets of the conveyor during operation and to remove material 40 therefrom by impact therewith and being provided with means for delivering an impact in proportion to the speed of the buckets.

3. In a trenching machine the combination 45 of, an endless conveyor, a plurality of buckets carried by said endless conveyor, and a bucket cleaner for removing material from said buckets by impact therewith, said cleaner being provided with means for co-operating therewith to exert a progressively 50 decreasing force against the material after the impact.

4. In a trenching machine the combination 55 of, an endless conveyor, buckets carried by said conveyor, and a cleaner associated with said conveyor and arranged to sweep material from said buckets, said cleaner being mounted for swinging movement and provided with means for resisting the swinging 60 movement of the cleaner in at least one direction and by the inertia thereof.

5. In a trenching machine the combination 65 of, an endless conveyor, buckets carried by said conveyor, a boom for supporting said conveyor, a bucket cleaner for removing material from said buckets by a sweeping action, and a gravity device for resisting movement of the cleaner in at least one direction and returning the cleaner to a normal position, 70 said boom being formed to provide a housing and guideway for said gravity member.

TRULS LOKEN.
